His ATTORNEY.

UNITED STATES PATENT OFFICE.

DALE C. HUGHES, OF CLEVELAND, OHIO, ASSIGNOR TO GENERAL ELECTRIC COMPANY,
A CORPORATION OF NEW YORK.

INSULATING DEVICE.

1,203,343.

Specification of Letters Patent. Patented Oct. 31, 1916.

Application filed March 9, 1915. Serial No. 13,118.

To all whom it may concern:

Be it known that I, DALE C. HUGHES, a citizen of the United States, residing at Cleveland, county of Cuyahoga, State of Ohio, have invented certain new and useful 5 Improvements in Insulating Devices, of which the following is a specification.

My invention relates to electric incandescent lamps, and more especially to means 10 for insuring the proper insulation between the external conductors or leading-in wires which are used in connection with such lamps.

In the manufacture of incandescent lamps 15 the leading-in wires are sealed for a portion of their length in the flattened end of a short glass tube, the other end of which is open and around which the bulb is fused to form a seal. The leading-in wires extend through 20 the tube, and it is necessary to provide means for keeping them separate and insulated from each other throughout their length as, otherwise, a short circuit might occur. In the case of lamps which have been on the 25 market for some time the temperature is sufficiently low so that cotton or similar material may be used. However, in the case of a lamp such as that covered by Langmuir application Serial No. 762,327, filed April 30 19, 1913, it is necessary to employ a refractory material on account of the comparatively high temperature which is reached by the said lamps. One material which has 35 been used is asbestos or slag wool. A wad of this is inserted between the leading-in wires, and when the lamp is subsequently based it is necessary to cap the end of the tube to prevent foreign material from getting into the tube and causing a short circuit. Slag wool and other similar materials have the objection that they are more or less hygroscopic and their accumulation of moisture will in time produce a short circuit or leakage of the current.

40 The object of my invention is to provide an efficient insulating and separating means which will not have this objectionable characteristic.

Moreover, it is the object of my invention 45 to provide means which will obviate the necessity of a double operation to secure the insulation and capping of the tube.

Further advantages of my invention will appear from the detailed description which

follows, and from the accompanying drawing.

In the drawing, Figure 1 is an elevation, partly in section, of an electric incandescent lamp embodying my invention. Fig. 2 is a perspective of the plug comprised by my invention.

In the drawing, 10 is an electric incandescent lamp of the general character disclosed in the Langmuir application hereinbefore referred to. The said lamp comprises a tube 11 and the external flange 12 at the upper end of the same is fused to the bulb 13. The leading-in wires 14 are connected by means of the platinum or other sealing wire 15 to the metallic support 16 for the filament 17. In the making of the lamp the end of tube 11 is fused and flattened around the wires 15 and the ends of wires 14 and 16 so as to constitute a hermetic seal. As shown in Fig. 2, the plug 18 is hollow and is open at one end 19 and tapered gradually to the closed end 20. Grooves 21 are formed in the sides of the plug and are diametrically opposite. The plug 18 is of such size that it extends into the tube 11 and fits snugly near its outer end with the sides of said tube. The leading-in wires are caused to engage the grooves 21 and are then crimped over the edge of the plug 18 so as to hold the same securely in place.

It will be apparent that after the insertion of the plug and the connecting of the wires as above described, the lamp may be based without further capping of the tube 14. It will be apparent, also, that the leading-in wires can not by any possibility short circuit, as they are held securely within the grooves 21. This is true even should there be a rotation of the plug 18, as each leading-in wire will be carried in the rotation by its respective groove. The plug 18 is composed preferably of glass, although it is possible to use other refractory material. The construction of the plug is such that it can be very easily handled by inserting the end of the finger thereinto in the same manner as into a thimble.

What I claim as new and desire to secure by Letters Patent of the United States, is:

1. An electric incandescent lamp comprising a bulb, a glass tube sealed to the said bulb and extending thereinto, leading-in wires passing through the said tube and

- sealed in one end thereof, and a refractory plug closing the other end of the said tube, said plug being grooved to receive the said leading-in wires.
6. 2. An electric incandescent lamp comprising a bulb, a tube sealed to said bulb and extending thereinto, leading-in wires passing through said tube and sealed in one end thereof, and a removable plug of refractory material closing the other end of said tube and having grooves therein to receive the said leading-in wires, said leading-in wires being crimped over the end of the said plug to hold the same in place.
10. 3. An electric incandescent lamp comprising a bulb, a tube sealed to said bulb and extending thereinto, leading-in wires passing through the said tube and sealed to one end thereof, and a hollow plug of refractory material closing one end of the said tube 20 and having grooves in its outer surface to receive the said leading-in wires.

In witness whereof, I have hereunto set my hand this 5th day of March, 1915.

DALE C. HUGHES.
